UNITED STATES PATENT OFFICE.

ARTHUR C. DAMAN, OF DENVER, COLORADO.

FLOTATION APPARATUS.

1,285,061.

Specification of Letters Patent. Patented Nov. 19, 1918.

Application filed April 28, 1917. Serial No. 165,155.

To all whom it may concern:

Be it known that I, ARTHUR C. DAMAN, a citizen of the United States, residing at Denver, in the county of Denver and State 5 of Colorado, have invented certain new and useful Improvements in Flotation Apparatus, of which the following is a specification.

My invention relates to new and useful improvements in apparatus for the separation 10 of minerals from the gangue with which they occur in association in metalliferous ores, by what is commonly known as the flotation process and its primary object resides in the provision of a combination of devices 15 which coöperatively produce a thorough aeration and emulsification of ore pulp and by an automatically repeated treatment of the same, effect a complete separation of the minerals from the gangue with which they 20 were associated.

With the above and other objects in view, all of which will fully appear in the course 25 of the following description, my invention consists of features of construction, arrangement of parts and combinations of devices shown in the accompanying drawings in the various views of which like parts are similarly designated and in which

Figure 1 is a vertical section taken on a 30 plane of the axis of my improved flotation apparatus,

Fig. 2, a transverse section along the line 2—2, Fig. 1,

Fig. 3, a similar section taken along the 35 line 3—3, Fig. 1, and Fig. 4 an enlarged section on the line 4—4, Fig. 1.

Referring more specifically to the drawings, my improved separating apparatus comprises in its preferred form a container 40 2 having the form of an inverted cone which at its lower end has a valve controlled opening 3 through which the gangue or valueless matter of the ore pulp under treatment is discharged.

45 Suspended centrally within the container from a suitable supporting structure 4 by means of laterally projecting arms 5, is an open-top cylinder 6 which in the operation of the machine provides a chamber in which 50 the pulp under treatment is aerated and emulsified.

The cylinder 6 has its lower portion divided into a central agitating and aeration compartment 7 and a surrounding passage

8 of restricted dimensions by means of an 55 open-top vessel 9 which is secured in spaced relation to the circumferential and bottom surfaces of the cylinder.

A downwardly converging apron 10 disposed above the passage 8 serves as a hopper to direct inflowing material toward the center of the compartment 7 and it also separates the pulp which enters the compartment, from the outflowing matter which overflows the edge of the vessel into the surrounding passage as will hereinafter be more fully explained.

The partitioning apron which extends inwardly from the circumferential wall of the chamber 6 is composed of a number of annular plates which are stepped in spaced relation to each other to provide slots for the passage of air between them.

A ring 13 supported upon the cylinder 6 by means of legs 14 provides a bearing for 75 an annular gear wheel 15 which meshes with a pinion 16 on a shaft 17 mounted for rotation in boxes 18, on a supporting structure 19.

The annular gear carries a plurality of 80 radially projecting blades 20 provided with flexible wipers 20^a which in the operation of the machine, skim the froth formed upon the surface of the contents of the container into two or more launders 21 disposed transversely of the container between its peripheral edge and that of the cylinder 6.

Another launder 22 surrounding the container at its peripheral edge, is auxiliary to the transverse launders by receiving the 90 material discharged across the edge of the tank and an annular dash plate 23 preferably secured to the cylinder 6 and extending above the top of the launders 21 at the inner edges thereof, prevents the froth from 95 being drawn into the chamber 6 by the suction produced in the operation of the apparatus as will hereinafter be described.

The launders 21 which slope to the circumferential wall of the conical container, 100 connect at their lower ends with discharge conduits 24 and the peripheral launder 22 is provided with one or more outlets 22^a through which the accumulated froth is removed.

A second shaft 25 supported in bearings 26 on the structure 19 extends through the concentric gear 15 and the bearing ring 13

and carries at its lower end a suction-wheel 27 which is disposed within the compartment 7, and a propeller 28 which is arranged beneath the bottom of the cylinder 6.

5 Both shafts are connected with a conveniently located source of power by means of belts running around pulleys 29 and 30 at their upper ends.

10 The suction wheel 27 consists of an open-top cylindrical vessel which has in its circumferential wall, a series of oblique vanes or fan-blades 31 which when the wheel revolves, create a suction of air through the open top of the vessel outwardly through 15 the spaces or ports between them.

The propeller consists of a hub secured at the end of the shaft 25 and a series of vanes which radiate equidistantly therefrom.

20 A bowl 32 placed beneath the propeller has an upturned rim to deflect the material thrown outwardly by the motion of the same, for the purpose of compelling it to assume an upward course in the container, and baffles 33 extending radially between said rim 25 and the bottom portion of the cylinder 6, have the two-fold function of suspending the bowl from the cylinder and of counter-acting the whirling motion imparted to the material by the rotary movement of the propeller.

25 In case the character of the ore under treatment requires a supply of air additional to that beaten into and entrained by the pulp in the operation of the mechanism hereinbefore described, an air-chamber composed of a plurality of screen-covered, separately removable sections 34 may be applied to the wall of the container to introduce compressed air in innumerable fine jets into 40 the pulp as it dashes outwardly across the edge of the bowl.

30 The sections of which the air-chamber is composed are connected with a source of air under pressure, by means of pipes 35 and 35 they are supported for ready removal, upon an angular bracket 36 fastened to the wall of the container.

35 In the operation of my improved flotation apparatus the ore pulp together with a suitable percentage of oil or other agent having a selective affinity for the sulfid particles contained therein, is fed into the rotating suction wheel through the medium of a feed-pipe 37 which delivers its discharge onto the downwardly sloping apron 10.

The suction-wheel draws by its rapid rotary movement a current of air of large volume into its interior where it mixes with the pulp and the oil.

40 The emulsion thus obtained is forcibly discharged through the ports between the fan blades 31 of the wheel, partially in the form of a froth, and in a whirling current overflows the peripheral edge of the vessel 9 underneath the partitioning apron 10, to

enter the surrounding passage 8. The amount of liquid fed into the vessel 9 is so regulated that the wheel will cause a layer of liquid to be maintained against the wall of the vessel and to flow over its top.

70 The material moving downwardly through the passage 8 is discharged onto the central portion of the propeller through an opening 38 in the bottom of the cylinder 6, and by the rotary movement of the propeller, is 75 after further agitation, aeration and emulsification, violently discharged across the peripheral edge of the subjacent bowl 32.

75 The baffles 33 at the circumference of the bowl counteract the whirling motion imparted to the liquid mass by the rotary movement of the propeller and the upturned edge of the same deflects the material to assume an upwardly directed course, with the result that the heavier particles not entrapped in the froth produced by the intermixture of pulp, oil and air, are thrown inwardly toward the upper edge of the cylinder 6 while the froth carrying a part 90 of the sulfids in suspension rises to the surface of the liquid mass to be removed into the launders 21 by the action of the rotary skimmers 20.

95 The part of the material not converted into a froth by the aforesaid operation, passes over the edge of the chamber 6 and falling upon the sloping apron, re-enters the compartment 7 together with the fresh charge constantly supplied through the feed conduit.

100 The material is thus repeatedly treated in the above described manner until all of its sulfids are entrapped in the froth produced by the violent agitation and simultaneous aeration of the pulp and oil, and 105 the gangue contained in the pulp upon passing across the edge of the bowl subsides to the bottom of the container where it gradually accumulates to be removed through the valve controlled outlet 3.

110 It will be seen that the rotary elements of my invention effect a rapid circulatory movement of the pulp through the passages provided by the relatively stationary parts of the apparatus, while air in large quantities is drawn and beaten into the moving mass by the action of the suction wheel as well as by the movement of the propeller and also by entrainment as the material moves through the restricted passage 8.

115 In case an additional supply of air is required to advance or complete the frothing action, the sections of the air chamber are placed in connection with a source of air 120 under pressure to inject air in fine streams into the mass as it enters the portion of the container surrounding the agitation chamber, across the edge of the upturned rim of 125 the bowl.

The suction wheel which preferably is closed at its bottom, may be made of any desired form, its primary function being to draw air into the pulp constantly fed thereinto across the sloping apron and to thoroughly emulsify the pulp with the oil and air by forcing it through its narrow ports in a violently whirling current.

The spaces between the plates of which the apron is composed, admit air into the material as it enters the narrow passage between the vessel 9 and the cylinder 6, and the rotary movement of the propeller also induces an inflow of air, while in association with the bowl, it produces the current which causes the upward movement of the froth and the repeated treatment of the matter not included therein.

It is manifest that successful flotation of ore particles aside from adding to the pulp the proper percentage of oil or other reagent, depends primarily on the introduction of air in large volumes and the thorough emulsification of the entire mass. It is but seldom that these actions are completed in one operation, to an extent sufficient to extract all or nearly all the minerals contained in the ore, and repeated treatments are for this reason a common requirement of the majority of flotation machines at present in use.

It will be readily seen that in the operation of the present machine, the repeated treatment of the material is automatically effected in one operation, that the introduction of the air is limited only by the velocity of the rotating parts, and that a most thorough intermixture of the ingredients must be the infallible result of the co-operative arrangement of the parts of the mechanism.

It will furthermore be seen that the mechanism may be made and assembled as a unit suitable for application to any tank or receptacle of the desired dimensions, it being obvious that while a tank of the form shown in the drawings is preferable, a differently shaped container may be effectively used in the operation of the more essential elements of the apparatus.

Furthermore I desire it understood that while I have shown the operating parts of the mechanism in the best form at present known to me, variations in their construction and arrangement, other than those hereinbefore referred to, may be resorted to within the spirit of my invention as defined in the following claims:

1. Apparatus for separating minerals by flotation, comprising in combination with a suitable container, a chamber therein, a suction-wheel having a rotary movement in said chamber and composed of an open-top vessel having peripheral openings for the discharge of its contents, and means for feeding

material into the wheel, the chamber having an outlet for the material after it is discharged through the openings of the wheel.

2. Apparatus for separating minerals by flotation, comprising in combination with a suitable container, a chamber therein, a suction-wheel having a rotary movement in said chamber and composed of an open-top vessel having peripheral ports extending vertically along the greater part of its depth for the discharge of its contents, and means for feeding material into the wheel, the chamber having an outlet for the material after it is discharged through the ports of the wheel.

3. Apparatus for separating minerals by flotation, comprising in combination with a suitable container, a chamber therein, a rotary, ported suction-wheel in said chamber, a rotary propeller beneath the same, and means for feeding material into said wheel, said chamber having an outlet for the passage of the material after it is discharged through the ports of the wheel, onto the propeller.

4. Apparatus for separating minerals by flotation, comprising in combination with a suitable container, a chamber having an outlet therein, a rotary, ported suction wheel in said chamber, means for feeding material into the wheel, and a rotary propeller disposed outside said chamber, to engage material discharged through the outlet of the same.

5. Apparatus for separating minerals by flotation, comprising in combination with a suitable container, a chamber having an outlet therein, a rotary, ported suction-wheel in said chamber, means for feeding material into the wheel, a rotary propeller disposed outside said chamber, to engage material discharged through the outlet of the same, and a deflective surface disposed with relation to said propeller to compel material impelled thereby to assume an upward course in the container.

6. Apparatus for separating minerals by flotation comprising in combination with a suitable container, a chamber having an outlet therein, a rotary, ported suction wheel in said chamber, means for feeding material into the wheel, a rotary propeller disposed outside the chamber to engage material discharged through the outlet of the same, and a deflecting surface disposed with relation to the propeller to compel material impelled thereby to assume an upward course, said chamber having an inlet to admit material from the container.

7. Apparatus for separating minerals by flotation comprising in combination with a suitable container, a chamber having an outlet therein, a rotary, ported suction wheel in said chamber, means for feeding material into the wheel, a rotary propeller disposed outside the chamber to engage material discharged through the outlet of the same, a

deflecting surface disposed with relation to the propeller to compel material impelled thereby to assume an upward course, and baffles on said surface to counteract the whirling movement imparted to the material by rotation of the propeller, said chamber having an inlet to admit material from the container.

8. Apparatus for separating minerals by flotation, comprising in combination with a suitable container, a chamber having an outlet therein, a rotary, ported suction wheel in said chamber, means for feeding material into a wheel, a rotary propeller disposed outside the chamber to engage material discharged through the outlet of the same, a deflecting surface disposed with relation to the propeller to cause material impelled thereby to assume an upward course, said chamber having an inlet above said apron to admit material.

9. Apparatus for separating minerals by flotation, comprising in combination with a container, a chamber having an outlet therein, an open-top vessel spaced from the wall of said chamber to provide a passage for material overflowing its top, to said outlet, a rotary, ported suction-wheel within said vessel, means for feeding material into said vessel, a propeller disposed outside the chamber to engage material discharged through the outlet thereof, and a deflecting surface disposed with relation to the propeller to cause material impelled thereby to assume an upward course.

10. Apparatus for separating minerals by flotation, comprising in combination with a container, a chamber having an outlet therein, an open-top vessel spaced from the wall of said chamber to provide a passage for material overflowing its top, to said outlet, a rotary, ported suction wheel within said vessel, means for feeding material into said wheel, a propeller disposed outside the chamber to engage material discharged through the outlet thereof, and a deflecting surface disposed with relation to the propeller to cause material impelled thereby to assume an upward course, said chamber having an inlet to admit material.

11. Apparatus for separating minerals by flotation comprising in combination with a container, a chamber having an outlet therein, an open-top vessel spaced from the wall of said chamber to provide a passage for material overflowing its top, to said outlet, a rotary, ported suction wheel within said vessel, an apron extending over said passage and adapted to direct material fed thereonto into the wheel, and means for feeding material onto said apron.

12. Apparatus for separating minerals by flotation, comprising in combination with a container, a chamber having an outlet therein, an open-top vessel spaced from the wall

of said chamber to provide a passage for material overflowing its top, to said outlet, a rotary, ported suction wheel within said vessel, an apron extending over said passage and adapted to direct material fed thereonto, into the wheel, means for feeding material onto said apron, a propeller disposed outside the chamber to engage material discharged through said outlet, and a deflecting surface disposed with relation to the propeller to cause material impelled thereby, to assume an upward course, said chamber having an inlet above said apron to admit material.

13. Apparatus for separating minerals by flotation comprising in combination with a suitable container, a chamber having an outlet therein, means for feeding material into said chamber, an agitating element in said chamber, and an impellent element disposed outside said chamber to engage material discharged through said outlet.

14. Apparatus for separating minerals by flotation, comprising in combination with a suitable container, a chamber having an outlet therein, means for feeding material into said chamber, an agitating element in said chamber, and an impellent element disposed outside said chamber to engage material discharged through said outlet.

15. Apparatus for separating minerals by flotation, comprising in combination with a suitable container, a chamber having an outlet therein, means for feeding material into said chamber, an agitating element in said chamber, and an impellent element disposed outside said chamber to engage material discharged through said outlet, said chamber having an inlet to admit material from the container.

16. Apparatus for separating minerals by flotation, comprising in combination with a container, an open-top chamber having an outlet in its bottom, an open-top vessel spaced from the surface of said chamber to provide a passage for material overflowing the edge of the vessel, to said outlet, a rotary, ported suction-wheel in said vessel, an apron extending over said passage and adapted to direct material fed thereonto, into the suction-wheel, a rotary propeller beneath the chamber to engage material discharged through the outlet, and a bowl beneath the propeller having a deflecting rim to cause material impelled by the propeller to assume an upward course.

17. Apparatus for separating minerals by flotation, comprising in combination with a container, an open-top chamber having an outlet in its bottom, an open-top vessel spaced from the surface of said chamber to provide a passage for material overflowing the edge of the vessel, to said outlet, a rotary, ported suction wheel in said vessel, an apron extending over said passage and

adapted to direct material fed thereinto, into the suction-wheel, a rotary propeller beneath the chamber to engage material discharged through the outlet, a bowl beneath the propeller, having a deflecting rim to cause material impelled by the propeller to assume an upward course, and baffles in said bowl to counteract the swirling movement imparted to the material by rotation of the propeller.

18. Apparatus for separating minerals by flotation, comprising in combination with a container, an open-top chamber having an outlet in its bottom, an open top vessel 15 spaced from the surface of said chamber, to provide a passage for material overflowing the edge of the vessel, to said outlet, a rotary, ported suction wheel in said vessel, an apron extending over said passage and 20 adapted to direct material fed thereinto, into the suction-wheel, a rotary propeller beneath the chamber to engage material discharged through the outlet, a bowl beneath the propeller having a deflecting rim to 25 cause material impelled by the propeller to assume an upward course, and an air-chamber disposed to inject air into the material after it leaves said bowl.

19. Apparatus for separating minerals by 30 flotation, comprising in combination with a container, a chamber having an outlet therein, an open-top vessel spaced from the wall of said chamber to provide a passage for material overflowing its top, to said outlet, 35 a rotary, ported suction wheel within said vessel, an apron extending over said passage and adapted to direct material fed thereonto, into the wheel, and means for feeding material onto said apron, said apron having 40 spaces for the passage of air.

20. Apparatus for separating minerals by 45 flotation, comprising in combination with a container, a chamber having an outlet therein, an open-top vessel spaced from the wall of said chamber to provide a passage for material overflowing its top, to said outlet, a rotary, ported suction wheel within 50 said vessel, an apron extending over said passage and adapted to direct material fed thereonto, into the wheel, and means for feeding material onto said apron, said apron being composed of stepped plates spaced for the passage of air.

21. Apparatus for separating minerals by 55 flotation, comprising an open-top chamber

having an outlet in its bottom, an open top vessel spaced from the surface of said chamber, to provide a passage for material overflowing the edge of the vessel, to said outlet, a rotary, ported suction wheel in said vessel, an apron connected to the chamber, extending over said passage and adapted to direct material fed thereonto, into the suction-wheel, a rotary propeller beneath the chamber to engage material discharged through the outlet, and a bowl attached to the chamber beneath the propeller and having a deflecting rim to cause material impelled by the propeller to assume an upward course, a device for suspending the chamber 70 within a container, and means for the rotary suspension of said suction-wheel and said propeller.

22. Apparatus for separating minerals by flotation, comprising in combination with a 75 container, a chamber, a rotary, ported suction wheel therein, and a rotary propeller outside the chamber, said chamber having an outlet for the discharge of material onto the propeller, and a restricted passage to 80 conduct material discharged from the suction wheel to said outlet.

23. Apparatus for separating minerals by flotation, comprising in combination with a 85 container, a chamber therein, a suction-wheel having a rotary movement in said chamber and composed of an open-top vessel having in its circumferential surface a series of oblique vanes and between them ports for the discharge of its contents, and means 90 for feeding material into the wheel, the chamber having an outlet for the material after it is discharged through the ports of the wheel.

24. Apparatus for separating minerals by 95 flotation, comprising in combination with a container, a chamber having an outlet therein, a propeller outside said chamber, a deflective surface to induce material impelled by said propeller to assume an upward 100 course in the container, and means for feeding material into said chamber, the chamber having an inlet to receive material during its said upward course.

In testimony whereof I have affixed my 105 signature in presence of two witnesses.

ARTHUR C. DAMAN.
